United States Patent Office

Des. 212,323
Patented Oct. 1, 1968

212,323

BUILDING STRUCTURE

Igor Sazevich, San Francisco, Calif., assignor to Rian's
Incorporated, Portland, Oreg., a corporation of Oregon

Filed Mar. 4, 1968, Ser. No. 18,838

Term of patent 14 years

(Cl. D13—1)

FIG. 1

FIG. 2

FIG. 3

FIG. 4

FIG. 5

FIG. 1 is a front elevational view of a building structure, showing my new design;

FIG. 2 is a rear elevational view thereof;

FIG. 3 is an elevational view of one side thereof;

FIG. 4 is an elevational view of another side thereof; and

FIG. 5 is a top plan view thereof.

I claim:

The ornamental design for a building structure, as shown.
